(57) **CLAIM**

The ornamental design for a handle for battery operated toothbrush, as shown and described.

DESCRIPTION

FIG. 1 is a perspective view of a first embodiment of a handle for battery operated toothbrush;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof;

FIG. 8 is an enlarged view of the top plan thereof.

FIG. 9 is a perspective view of a second embodiment of a handle for battery operated toothbrush;

FIG. 10 is a front view thereof;

FIG. 11 is a right side view thereof;

FIG. 12 is a rear view thereof;

FIG. 13 is a left side view thereof;

FIG. 14 is a top plan view thereof;

FIG. 15 is a bottom view thereof; and,

FIG. 16 is an enlarged view of the top plan thereof.

Broken lines are used in the drawings to designate parts of the handle for battery operated toothbrush that form no part of the claim.
